UNITED STATES PATENT OFFICE.

CHARLES FLAX, OF NEW YORK, N. Y.

DESIGN FOR A MEMBER FOR BAG-FRAMES.

SPECIFICATION forming part of Design No. 37,011, dated June 28, 1904.

Application filed March 29, 1904. Serial No. 200,637. Term of patent 7 years.

To all whom it may concern:

Be it known that I, CHARLES FLAX, a subject of the Czar of Russia, and a resident of the city of New York, borough of Manhattan, 5 in the county and State of New York, have invented a new, original, and ornamental Design for a Member of a Bag-Frame, reference being had to the accompanying drawing, in which the figure is a perspective view of a 10 member of a frame for bags, showing my design.

I claim as new and desire to secure by Letters Patent—

The ornamental design for a member of a bag-frame herein shown.

CHAS. FLAX.
